CLAIM

The ornamental design for a glass rinser, as shown and described.

DESCRIPTION

FIG. 1 is a front, top perspective view of a glass rinser design showing the first embodiment of my new design.

FIG. 2 is a front view of a glass rinser.

FIG. 3 is a rear view of a glass rinser.

FIG. 4 is a left view of a glass rinser.

FIG. 5 is a right view of a glass rinser.

FIG. 6 is a top view of a glass rinser.

FIG. 7 is a bottom view of a glass rinser.

FIG. 8 is a bottom perspective view of a glass rinser.

FIG. 9 is a front, bottom perspective view of a glass rinser design showing the second embodiment of my new design.

FIG. 10 is a front view of FIG. 9.

FIG. 11 is a rear view of FIG. 9.

FIG. 12 is a left view of FIG. 9.

FIG. 13 is a right view of FIG. 9.

FIG. 14 is a top view of FIG. 9.

FIG. 15 is a bottom view of FIG. 9; and,

FIG. 16 is a top perspective view of FIG. 9.

The broken lines shown in the drawings depict portions of the glass rinser that form no part of the claimed design.

1 Claim, 16 Drawing Sheets
